UNITED STATES PATENT OFFICE

EMIL BRECHT, OF GUBEN, GERMANY

PROCESS AND MACHINE FOR FELTING BATS FOR HATS

Application filed February 28, 1929, Serial No. 343,298, and in Germany February 25, 1928.

This invention relates to a process and a machine for felting bats for hats, especially for preliminarily felting hair, tops or combed yarn, noils or other fibrous materials or mixtures of such fibrous materials. It is known to allow fibrous materials of different nature to be deposited on a so-called forming cone by means of a current of air. By this operation the materials assume a more or less loose texture. There are certain difficulties in further treating this loose fibrous mass deposited on the cone for the reason that it has a tendency of undergoing very easily an undesired deformation with the result that the mass is often damaged or destroyed in transport.

It is an object of the invention to transform such fibrous masses or bats into a state in which they can be easily and safely transported, the further treatment being thus rendered possible as desired. With this object in view the fibrous deposit on the cone is, according to this invention, subjected to a preliminary felting treatment which it is possible to continue if desired until the felt is finished.

According to the invention felting is effected by subjecting the bats exclusively prepared by means of a current of air to the action of two conical surfaces performing a relative rotary movement. Such felting method is known in itself, but it has never been applied to bats prepared exclusively by a forming operation by means of a current of air.

It was not probable that conical surfaces performing relative rotary movements would be applicable to bats prepared exclusively by forming by means of an air current without injuring this very delicate material. However, according to the present invention such treatment is rendered possible by applying special means.

The invention is based on the observation that it is possible to treat, with the conical surfaces referred to, such bats exclusively prepared by forming by means of an air current if before the outer conical surface is applied the bat is subjected to a condensation or compression by the action of a reduced pres-

sure maintained within the inner cone until the outer cone is tightly applied to the bat or fibrous material deposited on the inner cone. By this treatment the thickness of the bat is reduced and its resistance against deformation is increased. The inner cone carrying the bat being perforated as usual, the reduced pressure within the said cone will act upon the bat covering its outer surface. Instead of applying reduced pressure within the cone it is, of course, also possible to apply an increased pressure to the outer surface of the bat, e. g. by means of compressed air.

The upper or outer cone to be applied to the bat can consist of a single hollow body preferably perforated in the same manner as the lower or inner cone for the purpose of rendering possible or facilitating the application of steam and similar operations that may be necessary or desirable. It is, however, also possible to use a divided cone, the parts of which are applied to the lower cone by a suitable swinging operation.

The operator is free to proceed with the preliminary felting operation as far as necessary according to the conditions. As a rule, felting should be at least proceeded with until convenient removal of the bat under treatment from the cone and its safe transport is secured.

Cones of any usual description may be used for carrying the invention into practice, e. g. bright cones, that is to say cones having a working surface consisting of bright metal, preferably copper, or cones having their working surfaces covered with material permeable for air, such as tissues or the like.

In the accompanying drawing a machine adapted to carry out the process according to the invention is diagrammatically shown by way of example, but the invention is not limited to this form.

In the drawing,
 Fig. 1 is a front elevation of the machine, partly in section,
 Fig. 2 is a side elevation, partly in section,
 Fig. 3 is a plan view, and

Fig. 4 is a cross-section of a cone and ring of the machine.

- ⁵ *a* is the working table which in the example shown is adapted to receive two cones *b* and *b*¹ for carrying the bats. It is, however, possible to arrange any convenient number of cones. Each of these cones which are perforated as usual is carried by a ring, *c*, *c*¹, the cones being preferably provided with fingers ¹⁰ *d*, *d*¹ engaging corresponding notches *C*^{''} of the rings, see Fig. 4. The rings are arranged in recesses of cover plates *f*, *f*¹ carried by boxes *e*, *e*¹, the rings being carried by vertical shafts *g*, *g*¹ journalled in thrust bearings ¹⁵ *h*, *h*¹ carried by the working table *a*. Each of the said cover plates *f*, *f*¹ carries two vertical guiding rods *i*, *i*¹ adapted for guiding the upper cones *k*, *k*¹ which are preferably provided with suitable perforations. ²⁰ These cones *k*, *k*¹ are secured to arms *m*, *m*¹ having their free ends perforated to adapt them for sliding on the guiding rods *i*, *i*¹. For reciprocating these upper cones up and down and for further guiding them they are ²⁵ provided at their upper ends with rods *p*, *p*¹ passing through openings of a guiding arm *q* and through openings of a further guiding arm *q*¹ supported by a column carried by the working table. The lower ends of two chains ³⁰ *n*, *n*¹ are fixed to collars forming part of the rods *p*, *p*¹, said chains passing on guiding disks carried by the arm *q*¹ and being provided at their other ends with counter-weights *o*, *o*¹ balancing the weight of the upper cones ³⁵ and thus facilitating their up and down reciprocation.

A driving shaft *r* is suitably journalled in the table. This shaft is driven, as shown in Fig. 3, by means of a belt pulley and a belt ⁴⁰ from a suitable motor (not shown). In the example shown two eccentric disks *s*, *s*¹ are arranged on the said shaft *r*, eccentric rods *t*, *t*¹ being connected to arms *u*, *u*¹ fixed to the vertical shafts *g*, *g*¹ in such a manner that ⁴⁵ when the shaft *r* is rotated slight swinging movements are imparted to the arms *u*, *u*¹ which movements are transferred to the lower forming cones *b*, *b*¹ by means of the rings *c*, *c*¹ above referred to.

⁵⁰ Openings of the boxes *e*, *e*¹ issue into the ends of pipes *v*, *v*¹ suitably connected to an evacuating pump or the like (not shown), the said pipes being provided with throttle valves, one of which *w*¹ is shown in Fig. 2. ⁵⁵ The throttle valves can be adjusted through a lever by means of manually operated rods *w*, *w*¹. Steam pipes *y*, *y*¹ are arranged for supplying steam or hot water to the bats resting upon the forming cones *b*, *b*¹, the said pipes being provided with suitable valves and having their ends approximately situated in the plane of the rings *c*, *c*¹ and bent to rings *z*, *z*¹ provided with outlet openings. ⁶⁰

⁶⁵ The operation of the machine for performing the process according to the invention

will now be described reference being made only to one unit for the sake of clearness.

A bat is formed in the usual forming machine by depositing fibrous material on a cone such as *b*, by means of a current of air. ⁷⁰

⁷⁵ This cone *b* carrying the bat is then put on the ring *c*. Reduced pressure is applied by means of the pipe *v*, the bat being condensed or compressed by the action of the reduced pressure and its thickness being reduced e. g., from 4 centimeters to 2 centimeters or 1 centimeter. The upper cone *k* is then lowered to apply it to the bat on the cone *b*, the parts thus taking the position shown in the right half of Fig. 1. In this position the upper cone *k* prevents the bat from expanding and it is, therefore, possible to cut off the reduced pressure pipe when the cone *k* has been applied. It is not necessary to interrupt the eccentric drive of the rings, ⁸⁰ the arrangement of the lower cone, the action of the reduced pressure on the bat, the application of the upper cone and its removal not being inconveniently influenced thereby. If it is desired to apply steam the valve of ⁸⁵ the steam pipe *y* is opened, steam being thus allowed to rise through the perforated ring *z* and to escape through the perforations of the lower cone *b*, the material of the bat and the perforations of the upper cone *k*. ⁹⁰

⁹⁵ The ring *c* performing a slight reciprocating movement on its circular path, the lower cone *b* carried by this ring and secured against dislocation by the fingers *d* engaging the notches *C*^{''} of the ring will assume the same reciprocating movement on the circular path. The upper cone *k* being secured against such movement by its guiding parts the desired relative movement of the lower cone *b* and the upper cone *k* is obtained and will cause the felting effect. The degree of felting being thus under complete control, the felting operation may be proceeded with as required by the circumstances. In most of the cases a partly felting or preliminary felting will be sufficient. In other cases it may be preferable to proceed further. ¹⁰⁰

¹⁰⁵ If felting is completed to the desired degree which takes a relatively short time the steam is cut off and the upper cone *k* is lifted; it is now possible to remove from the ring the lower cone *b* together with the preliminarily felted bat. ¹¹⁰

¹¹⁵ In many cases it is advisable to cool the bats before lifting the upper cone *k* in order to facilitate the separation of the upper cone *k* from the bat and the removal of the bat from the lower cone *b*. This cooling can be effected by simply allowing the bat to stand. It is preferable, however, to apply again reduced pressure for some time, cooled air from the atmosphere thus passing through the upper cone *k*, the bat and the lower cone *b* and rapidly cooling the bat. ¹²⁰

It is to be understood that the invention is not limited to the example described, but numerous variations obvious to those skilled in the art are possible without departing from the scope of the appended claims.

5 What I claim is:—

1. In a machine for felting bats for hats the combination of a perforated cone carrying the bat to be felted, pneumatic means connected to said cone and compressing the bat thereon, a second cone adapted to be tightly applied to the compressed bat carried by the first cone and preferably also perforated and means for imparting relative rotary movement to the said cones.

10 2. In a machine for felting bats for hats the combination of a perforated cone carrying the bat to be felted, pneumatic means connected to said cone and compressing the bat thereon, a second cone adapted to be tightly applied to the compressed bat carried by the first cone and preferably also perforated, means for imparting to the first cone a reciprocating rotary movement and means 25 for preventing the upper cone from rotating.

3. In a machine for felting bats for hats the combination of a perforated cone carrying the bat to be felted and supported by a 30 ring, pneumatic means connected to said cone and compressing the bat thereon, a second cone adapted to be tightly applied to the compressed bat carried by the first cone and preferably also perforated, means for imparting to the said ring a reciprocating 35 rotary movement and means for preventing the upper cone from rotating.

4. The process of manufacturing bats for hats which consists in pneumatically compressing the bat by internally applying reduced pressure, mechanically maintaining the bat in compressed condition, discontinuing the application of reduced pressure and felting the bat to the desired degree by subjecting the same to a relative rotary movement.

5. The process of preliminary felting of bats for hats which consists in first depositing the bat on a perforated cone exclusively 50 by blowing, then compressing the bat by applying reduced pressure within the cone, applying a second preferably also perforated cone to the bat, while maintaining the reduced pressure until the outer cone is tightly applied to the bat, and then imparting a 55 relative rotary movement to the cones for felting the bat to the desired degree.

6. A machine of the character described comprising a vertical shaft carrying a ring, 60 a lower cone mounted on said ring, fingers integral with said lower cone and adapted to engage notches provided in said ring, an arm on said vertical shaft, a main driving shaft actuating an eccentric and an eccentric rod pivotally connected to said arm to im-

part reciprocating rotary movement to said ring and lower cone.

7. A machine of the character described comprising a box, a pipe connected laterally thereto and adapted to be evacuated, a recessed cover plate on said box, a ring provided with notches and adapted to rotate adjacent to said recessed cover plate, a cone mounted on said ring, and fingers integral with said cone and engaging said notches to prevent relative motion therebetween.

75 8. A machine of the character described comprising a box, a pipe connected laterally thereto and adapted to be evacuated, a recessed cover plate on said box, a ring provided with notches and adapted to rotate adjacent to said recessed cover plate and a lower cone having fingers integral therewith which engage said notches in said ring.

80 In testimony whereof I have affixed my signature.
